LOCK

Henry Van Cott Holland, Westfield, N. J., assignor to The International Postal Supply Company, Brooklyn, N. Y., a corporation of New York

Application December 19, 1935, Serial No. 55,254

2 Claims. (Cl. 70—186)

This invention relates to locks and more particularly to locks of the reciprocating bolt type in which a plurality of bolts are employed. Specifically, the lock comprises a number of parts designed to be actuated successively, the operation of opening the lock depending on proper actuation of the parts by a suitable key.

In the embodiment of the invention herein illustrated the lock is applied to the meter mechanism of a so called "prepaid postage" machine. In addition to its function as an unlocking means the key also acts to hold the meter in positive engagement with the machine base better to insure engagement of the operating parts.

15. It is recognized that expert locksmiths by "feeling" with suitable implements, are frequently able to gage the lift of pins in locks wherein a plurality of reciprocable pins and rotary tumblers are used. It is also well known that certain types of reciprocating bolt locks may be picked with little or no difficulty. However, in most cases, it is only necessary that two suitable implements be employed to get the proper feel of the lock thus to enable one to open the lock without a key or to gage the measurements for duplicating the proper key. In order to obviate the possibility of enabling a person to open the lock by obtaining the feel of only two parts the present lock utilizes no less than three parts, each of which must be manipulated, and in the proper sequence, before the mechanism can be unlocked. Thus, it is practically impossible with two hands to obtain the feel of the combined parts, the lock on this account hindering unauthorized actuation.

35. The invention is described in detail in the following description thereof in which reference is had to the accompanying drawing wherein

40. Fig. 1 is a partial side elevation of a postage meter machine to which the lock is applied, parts thereof being broken away to illustrate the respective positions of the parts;

45. Fig. 2 is an enlarged front elevation of the lock shown in Fig. 1;

Fig. 3 is a side elevation of the lock;

Fig. 4 is a partial front elevation of a modified form of lock;

Fig. 5 is a section taken on line 5—5 of Fig. 4;

Fig. 6 is a perspective view of the end of the key; and

Fig. 7 is a section taken on line 7—7 of Fig. 1;

In the drawing the base of the postage machine is indicated at 11, the mechanism for driving the parts not being shown because it forms no part of the present invention. It is sufficient to state

that a motor or hand crank operates through gear 12 to turn shaft 13 which in turn rotates shaft 14. A suitable connection between shafts 13 and 14 is indicated at 15, this connection in the present instance comprising an elongated key 5 on the end of one shaft and a slot in the end of the other shaft. The meter is housed in housing 16 and is permanently geared to shaft 14. This housing and the meter contained therein are removable from the machine base and operating 10 mechanism attached to the base.

It is to be understood at the outset that, although the lock is shown and described as forming part of a specific machine, viz.: a postage metering machine, it is in nowise limited in its 15 use to a machine of this character. However, to enable a clear understanding of its use and operation it is illustrated in its application to this type of machine. It is therefore appropriate to state that, when the meter is removed from 20 its base, the shaft 14 is locked against unauthorized use of the printing mechanism attached to the shaft, the die normally being approximately 90° removed from an opening 17 in the housing when the shaft is locked. 25

The principal members comprising the lock are a plurality of similarly shaped reciprocable bars 18, 19 and a bell-crank lever 21 preferably disposed between bars 18 and 19 and pivoted on stud 22. Each of bars 18 and 19 is provided 30 with slots 23 cooperating with studs 22 and 24 to constrain the bars to move in a limited rectilinear path when the bars are moving to or from locking position. Furthermore, each bar is notched, as at 25, a pin 26 on lever 21 cooperating with the notches when the bars are in locking position to hold the bars in this position. Each bar has an angular projection or finger 27 thereon. Arm or finger 28 on lever 21, disposed between the bar fingers, is so disposed 40 with respect to these fingers when the bars are in locking position that its edge is spaced from the edges of fingers 27 as shown in Fig. 2. This is to insure movement of lever 21 by a key prior to lifting of the bars by the key as will be 45 hereinafter explained. 55

In Fig. 2 each bar is provided with a foot 29 engaging a notch 31 in each of two similar rocker levers 32 pivoted at 33 on the back of the meter housing back plate 34. A second notch 35 in each 50 lever 32 cooperates with fingers 36 in each of two independently movable bolts 37, 37', the latter members being guided in a slot 38 in boss 39 formed integral with the back plate. As shown in Fig. 2, bolts 37, 37' engage a slot 41 in shaft 55

14, thereby preventing rotation of the shaft. Assuming the normal position of the parts to be as shown in Fig. 2, that is, in locking position, it will be seen that bars 18 and 19 are held in this 5 position by springs 42, 43 and that lever 21 is maintained in the position shown by spring 44.

In Fig. 4 the bars 18, 19 are in substantial alignment with shaft 14, thus eliminating the interposed members 32, 37, 37'; the bars serving 10 as locking bolts. In this form of the invention the bars directly engage the shaft and the lock is represented in its simplest embodiment.

The key for actuating the locking mechanism is shown in Fig. 6 as a cylindrical shank 45 having 15 a key head 46 thereon, the head comprising a plurality of spaced parallel plate-like portions 47 connected by a web 48 at one side thereof but open along its other edge. These plates are so spaced that they are adapted to cooperate with 20 fingers 27, 28 to lift the same when the key is turned. Fingers 27, 28 lie between a plurality of parallel plates 49 between which are spacers 51, the thickness of the latter being substantially 25 that of fingers 27, 28 so that the fingers and plate-like portions of the key head may engage each other only if they register with each in a definite predetermined relation. Plates 49 and spacers 51 are secured to back plate 34 by pins 52. The back plate is provided with a suitably 30 shaped key-hole 53 to permit insertion of the key. Concentric with the key hole is an arcuate projection or abutment 54 disposed between the key-hole and fingers 27, 28 to prevent ready access to the fingers except by means of the key. 35 It will be seen from Fig. 6 that the plate-like portions 47 extend from the shank 45 to the outer edge of the key whereas the plates 47' have a depth substantially equal to that of web 48. A groove 48' is thus provided to permit the key to 40 be rotated without interference from projection 54.

In Fig. 1 it will be seen that shank 45 has reduced portions at 55 and 56. The shoulders at the ends of portions 55 are engageable with pin 45 57 secured to a part of base or housing 11' to limit longitudinal movement and removal of the key from base 11'. Spring 58 normally forces the key to the right in this figure. The other reduced part of shank 45 is threaded at 59 to receive nut 61 and is splined to a thumb piece 62 to 50 permit relative longitudinal movement of piece 62 and the shank. The shank is turned by the thumb piece, however. A short pin 63 on piece 62 is adapted to enter either of two holes 64, 65, in the back of housing 11'. It will be seen that 55 these holes are approximately 300° apart corresponding with the degree of rotation necessary to move the key from its initial position indicated in Fig. 1 with the key bit disposed vertically above the shank to the position shown in Fig. 4 to release the locking bars. Since springs 42, 43 and 44 normally tend to hold the bars in 60 their locking position it is evident that pin 63 must engage hole 65 to hold the bars in their released position.

65 When the meter housing is to be mounted on the base the key is turned to the position indi-

cated in Fig. 1. The meter is then held in a position where key-hole 53 registers with the key head and the parts of coupling 15 properly engaged. Thumb nut 59 is turned to draw the key head against back plate 34. The meter is 5 thus held firmly to the base.

When it is desired to release the locking mechanism, thumb piece 62 is turned to rotate the key through approximately 300° from its initial position in the direction indicated by the arrow 10 in Fig. 4. The key head first engages finger 28 on lever 21, releasing pin 21 from notch 25. Further rotation of the key brings the key head into engagement with fingers 27 on bars 18 and 19, raising the bars which, in turn, through rockers 32, release bolts 37, 37' from recess 41 in shaft 14. This permits rotation of the shaft. When key 46 is rotated clockwise (Fig. 2), bars 18 and 19 are drawn down by springs 42, 43 and, due to the shape of notch 35, the projection 32' on each of 20 the rockers 32 forces bolts 37, 37' into recess 41, thus preventing further rotation of the shaft.

It will be apparent that, when the meter and its housing are removed from the base of the machine, the key must be turned to permit the 25 locking bolts to fall into locking position. Similarly, in order for the machine to operate, the key must be rotated to release the bolts.

A preferred embodiment of the invention has been shown and described but such modifications 30 as fall within the scope of the appended claims may be made without departing from the basic invention.

What is claimed is:

1. A lock comprising a pair of reciprocable 35 members each having a notch thereon, means normally urging said members to locking position, a pivoted lever engageable with said notches when said members are in locking position, said members and said lever having projections extending angularly therefrom, and a plurality of spaced parallel plates between which said projections are disposed, the projection on said lever being engageable by a key to rock the pivoted member from engagement with said notches, the 40 projections on said members being thereafter engaged by continued movement of the key to reciprocate said members.

2. A lock comprising a pair of reciprocable members each having a notch thereon, means normally urging said members to locking position, a bell-crank lever pivotally mounted between said members, one arm of said lever having means thereon engageable with said notches when said members are in locking position, said members having projections extending angularly therefrom in substantial alignment with the other arm of said lever, and a plurality of spaced parallel plates between which said other arm and said projections are disposed, said other arm being engageable by a key to rock the bell-crank lever from engagement with said notches, the 50 projections on said members being thereafter engaged by continued movement of the key to reciprocate said members.
